(57) **CLAIM**

I claim the ornamental design for a device mount, as shown and described.

DESCRIPTION

FIG. 1 is a Perspective view of a device mount showing my new design;

FIG. 2 is a Bottom perspective view thereof;

FIG. 3 is a Back view thereof;

FIG. 4 is a Front view thereof;

FIG. 5 is a Right-side view thereof;

FIG. 6 is a Left-side view thereof;

FIG. 7 is a Top view thereof; and,

FIG. 8 is a Bottom view thereof.

1 Claim, 5 Drawing SheetsFIG. 1

FIG. 2

FIG. 3

FIG. 4

FIG. 5

FIG. 6

FIG. 7

FIG. 8
